CIRCUIT INTERRUPTER

Herbert L. Rawlins, Wilkinsburg, Pa., assignor to
Westinghouse Electric & Manufacturing Com-
pany, East Pittsburgh, Pa., a corporation of
Pennsylvania

Application March 30, 1934, Serial No. 718,267

30 Claims. (Cl. 200—117)

My invention relates to circuit interrupters and particularly to high voltage circuit breakers of the type which utilizes an explosive gas blast for extinguishing the arc formed incident to the interruption of the controlled circuit.

5 Expulsion circuit breakers usually comprise a tubular arc passage, a means, such as a fuse or a movable plunger, for drawing an arc within the tubular arc passage, and a means for producing 10 an explosive gas blast which flows longitudinally through the arc to effect its extinguishment. The efficiency and the reliability of operation of these devices depend to a great extent upon the amount and the chemical characteristics of the 15 gas which is caused to explosively flow through the arc during the circuit interrupting operation, and the principal problem of the art has always been the securing of an adequate volume of gas having a satisfactory chemical composition.

20 The most satisfactory structure so far evolved, secures the desired longitudinal blast of arc extinguishing gas by lining the arc passage with an insulating material which is capable of evolving large quantities of arc extinguishing gas and 25 which does not lose its insulating properties when placed in proximity to an electric arc. Preferably, the gas is inorganic in nature, readily condensable, and non-inflammable. All of these requirements are met by a lining composed of compressed boric acid, but, even this arrangement 30 has not proved entirely free from defects.

The evolution of gas from the surface of the lining of the arc passage depends to a great extent upon the intimacy of contact between the 35 lining and the arc, and it is obvious that the maximum possible evolution of gas (and the most efficient operation of the interrupter) will be effected when the arc completely fills the arc passage. Unfortunately, however, the magnitude 40 of the overload current on most present day circuits may vary through wide limits, and the physical dimensions of the arc likewise vary in direct proportion. It might appear that this would not create any serious difficulties, since the 45 arc passage could be made small enough to cause an intimate engagement between the lining and the surface of the smallest magnitude arc that might be drawn within the arc passage.

The problem is not so simply solved, because, 50 while intimate engagement between the lining of the arc passage and the arc is imperative, it is possible to have an arc passage which is too small. If this occurs and large magnitude arcs are drawn 55 therein the volume of gas generated may be sufficiently large to cause a rupture of the walls of

the arc passage, and even if the walls of the passage are not ruptured, the surfaces of those walls which are exposed to the arc may be heated sufficiently to become conducting and thereby make the interruption of the controlled circuit impossible.

This possibility of actual destruction of the circuit interrupter, or failure of the device to operate, during the occurrence of very heavy overload conditions, makes it necessary that the physical 10 dimensions of the arc passage shall be sufficiently large to permit an arc having the largest possible current magnitude, for the circuit on which the device is to be used, to be drawn within the arc passage without danger of rupture or excessive 15 heating. The obvious result of this is that for most circuits the arc passage must have a very considerable cross-sectional area, and when the interrupter is in use on such circuits, the low magnitude arcs produced by normal overloads will but 20 partially fill the arc passage. Under these conditions, only a small volume of arc extinguishing gas will be generated, and the efficiency of the interrupter will be very low. In fact, if the current magnitude of the arc is very small, it may 25 be impossible to extinguish it at all.

To overcome this difficulty, the prior art structures have utilized two arc passages, one of large cross-sectional area wherein arcs of heavy current magnitudes are interrupted, and one of 30 small cross-sectional area wherein arcs of a lower current magnitude are extinguished. This arrangement requires selective means for assuring that the arc shall be drawn in the proper passage, and is not entirely satisfactory from an 35 economic viewpoint.

The principal object of my invention is, therefore, to provide an improved expulsion circuit interrupter, of the type discussed above, that shall utilize but a single arc passage and that 40 shall be provided with means for assuring the satisfactory interruption of both small and large current arcs in that passage.

In carrying out the principal object of my invention, I provide a suitable means for defining 45 an arc passage, a plunger for drawing an arc within that passage, and a means of insulating material, which preferably forms a part of the plunger, movable into the arc passage only when arcs of small current magnitude have been or are 50 being drawn thereon. This means of insulating material restricts the cross-sectional area of the arc passage in such manner that even the low magnitude arcs are brought into intimate contact with the lining of the passage and as a re- 55

sult a sufficient volume of arc extinguishing gas will be evolved to assure a rapid and complete extinguishment of the arc.

A further object of my invention is to provide an expulsion type circuit interrupter with means for introducing a body of insulating material, itself capable of evolving an arc extinguishing gas when placed in proximity to an electric arc, into the arc passage thereof during the circuit opening operation.

Since, as pointed out above, the principal field for immediate application of my invention is in connection with expulsion circuit breakers of the plunger type, I shall hereinafter describe an embodiment of my invention as applied to such devices, without, however, in any way intending to restrict the scope of my invention except as indicated in the appended claims.

Referring to the single sheet of drawing:

20 Figure 1 is a sectional view, partially in elevation, of an expulsion type circuit interrupter embodying the principal features of my invention;

15 Fig. 2 is a sectional view taken on the line II-II of Fig. 1; and

25 Fig. 3 is a fragmentary detailed view, partially in section, showing a modified form of plunger for use with the circuit interrupter shown in Figs. 1 and 2.

The expulsion circuit interrupter shown in the drawing comprises, generally, a tube 1 of insulating material, which possesses sufficient strength to withstand the pressures ordinarily developed within these devices, a metallic cap or ferrule 3 for enclosing the upper end of the main insulating tube 1, and a second ferrule 5, having a centrally disposed opening 7 therein, for engaging the lower end of the insulating tube. Both the upper and lower ferrules are adapted to be retained in position by means of suitable screw threads 9 and 11 formed in the cooperating portions of those members and the tube 1. A tubular member 13, of conducting material, having a threaded portion 15 at one end, which portion engages a similarly threaded portion 17 forming a part of the upper ferrule 3, is disposed within the main tube 1, both for the purpose of reenforcing the tube and for completing the electrical circuit from the upper ferrule to the annular plate 19 positioned beneath the lower end of the tubular member 13.

50 A cylindrical member 21, preferably of compressed boric acid or other gas generating material, having a centrally disposed passage 23 therein is positioned within the lower portion of the main tube 1. The passage 23 constitutes the arc passage, the arc being established therein by the movable plunger assemblage 25. The boric acid member 21 is retained in position within the main tube 1 by the annular plate 19, which engages the lower portion of the conducting tube 13, and the lower ferrule 5. The opening 27 in the annular plate 19 is of substantially the same dimensions as the arc passage 23, and that passage terminates in a funnel-shaped opening 29, the largest diameter of which is substantially the same as the opening 7 in the lower ferrule 5.

The plunger assemblage 25 comprises generally a rod or plunger having a conducting portion 31 for drawing the arc into the arc passage 23, an insulating portion 33 for limiting the cross-sectional area of the arc passage, an electro-responsive mechanical connection between the conducting and the insulating portions of the plunger, and means for moving the plunger

means through the arc passage. The conducting portion 31 comprises a circular rod of conducting material, the upper end 35 of which is threaded for engagement with a suitable threaded opening in the movable piston member 37. The piston member 37 is circular in outline and is of somewhat smaller diameter than the tubular conducting member 13 wherein it is adapted to move. The lower end of the conducting portion 31 of the plunger is provided with a section 39 of reduced cross sectional area. This reduced section is threaded for engaging the upper end of the insulating portion 33 and serves to provide an electro-responsive mechanical connection between the two portions of the plunger. The piston member 37 and with it the two mechanically connected portions of the plunger proper are biased in the direction of the upper ferrule, at all times, by a coil spring 41. Movement in this direction is prevented by a fusible element 43, one end of which fits within a suitable recess 45 in the upper or cap portion 47 of the insulating portion of the plunger, and the other end of which fits within a like recess 49 in the lower ferrule 5.

The insulating portion 33 of the plunger may be formed of a number of different materials. If the interrupter is to be used out of doors, it may be desirable to form that member of a ceramic material or other which will not absorb moisture. If the device is to be used indoors, the rod may be formed of fiber or other materials more or less hydroscopic. In either case the material should be capable of retaining its insulating properties when placed in proximity to an electric arc.

For certain applications, it may be desirable to form the insulating portion 33 of material which is capable of evolving an arc extinguishing gas when brought into proximity with an electric arc, this arrangement being particularly suitable for use on circuits wherein it is desirable to have the minimum possible arcing time. If boric acid or other structurally weak materials are used for this purpose, it is desirable to reinforce the plunger, and a structure of this type is shown in Fig. 1. The insulating portion 33 of the device shown in that figure is formed of a material which is structurally weak, and a tubular reenforcing member 51 is molded or formed integral therewith. This reenforcing member 51 is provided with a threaded portion 53 at its upper end, for engaging a cooperating threaded recess in metallic top or cap portion 47 of the insulating member 33.

This cap portion 47 is also provided with a second threaded recess 55 for engaging the threaded end of the reduced section 39 of the conducting portion 31 of the plunger. This recess 55 connects with the recess 45, which is provided for the reception of one end of the fusible element 43, and when the device is completely assembled the threaded end of the section 39 is screwed down onto the end of the fusible element 43 in order to complete the electrical circuit from the conducting portion 31 to the fusible element 43 and to mechanically connect the fusible element with the plunger.

The modified form of the insulating portion of the plunger illustrated in Fig. 3 is adapted for use with insulating materials having a sufficient mechanical strength to obviate the necessity for reenforcing the insulating portion 33 of the plunger or for providing a cap means. When such materials are used, the upper end of the

insulating rod 57 may be provided with a recess 58 for engaging one end of the fusible element 43 and a threaded opening 61 for engaging the cooperating threaded end of the conducting rod 31.

5 The electrical circuit through the fuse is comparatively direct. Beginning with the upper ferrule 3, the current flows successively through the tubular conducting member 13, the annular 10 plate 19, the flexible shunt 63 intermediate the annular plate 19 and the piston member 37, thence through the piston member 37 and the conducting portion 31 of the plunger 25 to the fusible element 43, and through that element 15 to the other ferrule 5.

Upon the occurrence of a predetermined moderate overload in the circuit controlled by the device, the fusible element 43 melts, thereby releasing the plunger and allowing that member 20 to be moved to the open-circuit position under the biasing action of the spring 41. The conducting portion 31 of the plunger, by virtue of this movement draws the arc into the arc passage 23 and at the same time causes the entry 25 of the insulating portion 33 of the plunger into that passage. The insulating portion 33 restricts the cross-sectional area of the arc passage and brings the arc into intimate contact with the surface of the boric acid lining 21. A considerable 30 amount of water vapor is evolved as a result of this intimate contact, and since the only way that this vapor can vent is through the opening in the lower ferrule 5, a rapidly outflowing blast of arc extinguishing gas is produced which usually causes the interruption of the arc within 35 a few half cycles.

While as mentioned above it is necessary that the arc be brought into intimate contact with the gas evolving lining of the arc passage in order to secure satisfactory operation of the interrupter, it has been found that the dimensions of the several parts are not very critical. This results from the fact that on the ordinary circuits in use at the present time, overloads usually 40 fall within two general classes. The first of these classes includes the normal overloads resulting from excessive loading of the protected equipment, and their magnitude rarely exceeds the normal full load current by more than a few 45 hundred percent. The other class of overloads are those resulting from short-circuit or line-fault conditions, and these are ordinarily of very large magnitude—several thousand percent of the normal full load current. Thus, if the arc 50 passage and the means for limiting the area thereof are so designed that satisfactory interruption of the circuit can be secured for the usual range of normal overload values, and if a means is provided for taking care of the very large 55 overload which results from short circuits or the like, it is extremely improbable that the interrupter will not successfully operate under all possible conditions. This, in effect, is what is done with my improved type of circuit interrupter, which normally has a small arc passage 60 for interrupting the usual overload currents, and which is provided with electro-responsive means for increasing the area of the arc passage in order to successfully interrupt short circuits or 65 very heavy overload currents.

The operation of the device on heavy overloads or short circuit has been outlined above. Upon the occurrence of such conditions, the fusible element 43 melts, thereby releasing the plunger, that 70 member then being moved under the action of

the biasing spring 41 to establish the arc within the arc passage 23. However, due to the fact that the cross-section area of the section 39 of the conducting portion 31 of the plunger, which section is used for mechanically connecting the 5 conducting portion and the insulating portion of the plunger is of restricted cross-sectional area, considerable heating will occur at that point. If the magnitude of the arc current is sufficiently high this heating will result in the 10 fusion of the section 39 of the conducting member, and the insulated portion 33 of the plunger will be mechanically disconnected from the conducting portion 31, the result of this being that the arc is drawn within the arc passage, the entire 15 cross-sectional area of which is available for accommodating the large volumes of outflowing gas produced by a heavy magnitude arc.

It is possible under certain conditions, that the magnitude of the overload may be insufficient 20 to cause the insulating portion 33 of the plunger to be disconnected from the arc drawing portion 31 of the plunger before the upper end of the insulating portion has been drawn into the arc passage. Should this occur, when a very 25 large volume of gas is being generated within the arc passage 31, a very considerable force will exist upon the insulating portion 33 of the plunger, tending to move it out of the arc passage, and before the pressure within the arc 30 passage reaches a dangerous magnitude, the insulating portion 33 will be forcibly ejected from that passage. The point of fusion of the mechanical connection between the conducting and insulating portions of the plunger should be, of course, 35 properly adjusted, taking into consideration the characteristics of the circuit wherein the device is to be used and the interrupting capacity of the arc passage.

From the foregoing it will be seen that I have 40 provided an improved expulsion type circuit interrupter which is capable of satisfactorily interrupting arcs of small and of large magnitude within a single arc passage, this arrangement differing from the prior art devices which utilize 45 at least two arc passages for accomplishing the same result. In addition, I have disclosed certain preferred structural arrangements which are particularly suitable for carrying out the objects of my invention, and I have disclosed certain 50 types of material which are particularly adapted for use in conjunction with my invention.

While in accordance with the patent statutes I have disclosed the foregoing details of a practical embodiment of my invention, it is to be understood that many of these details are merely 55 illustrative, and that the broad features of my invention are capable of much wider adaptation than to the particular structure disclosed in this 60 application. I desire, therefore, that my invention shall be given the broadest reasonable construction, and that the claims shall be limited only by what is expressly stated therein and by the prior art.

65 I claim as my invention:

1. In an expulsion circuit interrupter, means defining a tubular passage substantially closed at one end, means, of a material capable of evolving 70 an arc extinguishing gas when placed in proximity to an electric arc, lining at least a part of said passage, means movable longitudinally in said passage to establish an arc therein, and means of insulating material, having a cross sectional area at least slightly less than the 75

- cross sectional area of said passage, movable in said passage during the circuit opening operation in order to restrict the cross-sectional area of the arc so as to effect an intimate engagement between the arc and a substantial portion of the gas evolving portion of said lining.
2. In an expulsion circuit interrupter, means defining an arc passage, means for producing a blast of gas which flows expulsively through said passage during each opening operation of said interrupter to extinguish the arc incident to such operation, and a plunger movable through said passage during the circuit opening operation, said plunger having a portion of conducting material for establishing said arc within said passage, and a portion of insulating material of less cross sectional area than said passage for limiting the cross-sectional area of at least a portion of said passage during the operation of said interrupter.
3. In an expulsion circuit interrupter, means defining a passage having substantially rigid walls, at least a portion of said passage being lined with a material capable of evolving an arc extinguishing gas when placed in proximity to an electric arc, means for establishing an arc within said passage, said passage having an opening for the escape of gas therefrom, means of insulating material movable into said passage, said movable means having a cross sectional area appreciably less than the cross sectional area of said arc passage, and means operable when but only when the magnitude of the current flowing through said arc is less than a predetermined value to cause said means of insulating material to enter at least a portion of said passage in order to effect a more intimate engagement between the arc and the gas evolving portion of said lining.
4. In a circuit interrupter for use with circuits subjected to overloads of widely varying magnitude, means defining a tubular passage at least a portion of which is lined with a material capable of evolving an arc extinguishing gas, when placed in proximity to an electric arc, means for establishing an arc within said passage, said passage having a vent for the escape of gas therefrom, and means, responsive to the magnitude of the current flowing in the circuit controlled by said interrupter, for controlling the cross-sectional area of at least a portion of said arc in order to effectively extinguish arcs of both large and small current magnitude.
5. In an expulsion circuit interrupter, means defining a tubular passage that is substantially closed at one end and open at the other, means of a material capable of evolving an arc extinguishing gas and capable of retaining its insulating qualities, when placed in proximity to an electric arc lining at least a portion of said passage, means of conducting material movable longitudinally within said passage to establish an arc therein, means of insulating material movable through said passage, said movable means having a cross sectional area at least slightly less than the cross sectional area of said passage, and means operable when but only when the magnitude of the current flowing through said arc is less than a predetermined value to cause said means of insulating material to enter said passage and to move through at least a portion thereof so as to restrict the volume of said passage in order to effect a more intimate engagement between said arc and the gas evolving portion of said lining.

6. In a circuit interrupter, means defining a passage, a plunger, and means for moving said plunger through said passage, during the circuit interrupting operation, said plunger having a portion of conducting material for establishing an arc within said passage and a portion of insulating material which, when moved into said passage, limits the cross-sectional area of at least a portion thereof, said portion of insulating material being mechanically connected to said arc drawing portion by means operable when the current flowing through said interrupter exceeds a predetermined value to mechanically disconnect said portion of insulating material from said arc drawing portion.

7. In a circuit interrupter, means defining a tubular passage at least a portion of which is lined with a material capable of evolving an arc extinguishing gas when placed in proximity to an electric arc, a plunger, and means operable upon the occurrence of predetermined conditions to move said plunger through said passage, said plunger including a portion of conducting material for establishing an arc within said passage and a portion of insulating material which, when moved into said passage, limits the cross-sectional area of at least a portion of said passage so as to effect an intimate engagement between said arc and said gas evolving portion of said lining, said portion of insulating material being mechanically connected to said arc drawing portion by means operable when the current flowing through said interrupter exceeds a predetermined value to mechanically disconnect said portion of insulating material from said arc drawing portion.

8. In a circuit interrupter for use with circuits subjected to overloads of widely varying magnitude, means defining a tubular passage at least a portion of which is lined with boric acid, means for establishing an arc within said passage, means for venting said passage, and means, responsive to the magnitude of the current flowing in the circuit controlled by said interrupter, for controlling the cross-sectional area of at least a portion of said passage wherein said arc is established in order to effectively extinguish arcs of both large and small current magnitude.

9. In a circuit interrupter, means defining a passage, a plunger, and means for moving said plunger through said passage, during the circuit interrupting operation, said plunger having a portion of conducting material for establishing an arc within said passage and a portion of insulating material which is capable of evolving an arc extinguishing gas, and which retains its insulating properties, when placed in proximity to an electric arc, said portion of insulating material, when moved into said passage serving to limit the cross sectional area of at least a portion of said passage, said portion of insulating material being mechanically connected to said arc drawing portion by means operable when the current flowing through said interrupter exceeds a predetermined value to mechanically disconnect said portion of insulating material from said arc drawing portion.

10. In an expulsion circuit interrupter, rigid means for defining the walls of an arc passage having a length at least several times its greatest width, means for establishing the arc incident to the opening of said interrupter within said arc passage, means for producing an explosive blast of gas through said passage for extinguishing said arc, and means for introducing a solid member of insulating material into said arc pas-

5 sage during the circuit opening operation, said member being of less cross sectional area than said arc passage in order that while it shall substantially restrict the area of said arc passage, so as to effect intimate engagement between said arc and the surfaces of said wall defining means and said member, it shall not close said arc passage sufficiently to restrict the free flow of said blast of gas which effects the 10 extinction of said arc.

11. In a circuit interrupter, rigid means for defining the walls of an arc passage having a length at least several times its greatest width, at least a portion of said passage being lined 15 with a material capable of evolving an arc extinguishing gas when placed in proximity to an electric arc, means for closing one end of said arc passage, the other end of said passage being open, at least during the circuit opening operation, means for establishing the arc incident to the opening of said interrupter within said arc passage, and means for introducing a solid member of insulating material into said arc passage during the circuit opening operation, said member being of less cross sectional area than said arc passage in order that while it shall substantially restrict the area of said arc passage, so as to effect intimate engagement between said arc and the surfaces of said wall defining means and 20 said member, it shall not, by its entry thereinto, entirely close said passage.

12. In an expulsion circuit interrupter, rigid means for defining the walls of a substantially cylindrical arc passage having a length at least 35 several times its width, at least a portion of said arc passage being lined with a material capable of evolving an arc extinguishing gas when placed in proximity to an electric arc, means for closing one end of said arc passage during each circuit 40 opening operation, the other end of said arc passage being open during each circuit opening operation, means for establishing the arc incident to the opening of said interrupter within said arc passage, and means for moving a solid member 45 of insulating material having a substantially cylindrical outer surface into said arc passage, in such manner that it is substantially concentric therewith, during the circuit opening operation, the diameter of said movable member being ap- 50 preciably less than the diameter of said arc passage in order that the movement of said member thereinto shall effect a substantial restriction of the area of said arc passage, so as to effect intimate engagement between said arc and the opposed concentric surfaces of said wall defining 55 means and said member, without entirely closing said arc passage.

13. In an expulsion circuit interrupter, means for defining the walls of an arc passage, means for establishing the arc incident to the opening of said interrupter within said arc passage, means for producing an explosive blast of gas through 60 said arc passage during the circuit opening operation of said interrupter for extinguishing said arc, and means for introducing a solid member of insulating material into said arc passage during the circuit opening operation of said interrupter, said member being so proportioned that it shall 65 substantially restrict the area of said arc passage 70 to effect intimate engagement between said arc and the surfaces of said wall defining means and said member and to permit the flow of said blast of gas between said wall defining means and said member.

75 14. In an expulsion circuit interrupter, means

for defining the walls of an arc passage, at least a portion of said means being formed of an insulating material which is capable of evolving an arc extinguishing gas when placed in proximity to an electric arc, means including a fusible element for establishing the arc incident to each opening operation of said interrupter within said arc passage, and means for introducing a solid member of insulating material into said arc passage during the circuit opening operation of said 10 interrupter, said member being so proportioned that it shall substantially restrict the cross sectional area of said arc passage to effect intimate engagement between said arc and the surfaces of said wall defining means and said member and 15 to permit the flow through said arc passage of the gas evolved from said insulating material.

15. In an expulsion circuit interrupter, rigid means having a substantially cylindrical passageway formed therein for defining the walls of an arc passage, means for establishing the arc incident to the opening of said interrupter within said arc passage, means for producing an explosive blast of arc extinguishing gas which flows longitudinally through said arc passage during 20 the opening operation of said interrupter for extinguishing said arc, said passage having an opening to permit the escape of gas therefrom, a plunger member having a substantially cylindrical outer surface which is adapted to be moved 25 into and through said arc passage during the operation of said interrupter, and means for moving said member in such manner that the longitudinal axis thereof will substantially coincide at all times with the longitudinal axis of said 30 passageway, said plunger member being formed at least partially of insulating material and being so proportioned that it substantially restricts the area of said arc passage to effect intimate engagement between said arc and the opposed surfaces of said wall defining means and said member 35 and to permit the flow of said blast of arc extinguishing gas through said opening.

16. In an expulsion circuit interrupter for use with circuits subjected to overloads of widely varying magnitude, rigid tubular means for defining the walls of an arc passage having a length at least several times its greatest width, means for establishing the arc incident to the opening of said interrupter within said arc passage, means for producing an explosive blast of gas which flows longitudinally through said arc passage during the circuit opening operation of said interrupter for extinguishing said arc, said passage having a vent to enable the blast of gas 50 to escape therefrom, and means responsive to the magnitude of the current flowing in the circuit controlled by said interrupter for controlling the cross-sectional area of at least a portion of said arc passage in order that said blast of gas shall 55 effectively extinguish arcs of both large and small current magnitude.

17. In an expulsion circuit interrupter, means for defining the walls of an arc passage, at least a portion of said wall defining means being 60 formed of an insulating material which is capable of evolving an arc extinguishing gas when placed in proximity to an electric arc, and a plunger movable through said arc passage during the operation of said interrupter, said plunger having 65 a portion of conducting material for establishing the arc incident to each opening operation of said interrupter within said passage and a portion of insulating material of less cross-sectional area 70 than said passage for restricting the cross-sec- 75

tional area of said passage so as to effect intimate engagement between said arc and the inner surface of said wall defining means, said insulating portion being so proportioned to permit the flow of gas evolved from said insulating material by said arc through said arc passage.

18. In an expulsion circuit interrupter, rigid means having a substantially cylindrical passage-way formed therein for defining the walls of an 10 arc passage, at least a portion of said wall defining means being formed of an insulating material which is capable of evolving an arc extinguishing gas when placed in proximity to an electric arc, and a substantially cylindrical 15 plunger movable longitudinally through said arc passage during the operation of said interrupter, said plunger being disposed substantially concentric with said arc passage at all times and having a portion of conducting material for est- 20 establishing the arc incident to each opening operation of said interrupter within said arc passage and a portion of insulating material of less cross sectional area than said arc passage for restricting the cross-sectional area of said arc passage, 25 so as to effect intimate engagement between said arc and the opposed surfaces of said wall defining means and said plunger, said insulating portion being so proportioned to permit the flow of gas evolved from said insulating material by 30 said arc through said passage

19. In a circuit interrupter, means for defining the walls of an arc passage, means for establishing the arc incident to each opening operation of said interrupter within said arc passage, a solid 35 member, which is formed at least partially of insulating material, movable into said arc passage to limit the cross-sectional area thereof, means for moving said solid member into said arc passage during the operation of said inter- 40 rupter, and a current responsive means intermediate said movable member and said means for moving that member, said last mentioned means being operable to disconnect said movable member from said means for moving that mem- 45 ber when the current flowing through said interrupter exceeds a predetermined value.

20. In an expulsion circuit interrupter, tubular means for defining a closure for said interrupter, means within said closure for defining an 50 arc chamber and a spring chamber, a plunger arranged for movement through said arc chamber, spring means disposed within said spring chamber which normally biases said plunger to the open circuit position, and electro-responsive 55 means which normally retains said plunger in the closed circuit position against the biasing force of said spring means, said plunger having a portion of conducting material movable through said arc chamber during the operation 60 of said interrupter to establish the arc incident to each opening operation of said interrupter therein and a portion of insulating material also movable through said arc chamber during each 65 operation of said interrupter, said insulating portion being so proportioned that while it shall substantially restrict the volume of said arc chamber, it shall not completely close that chamber.

21. In an expulsion circuit interrupter, tubular 70 means for defining a closure for said interrupter, means within said closure for defining an arc chamber and a spring chamber, said arc chamber being open at least at one end thereof during each opening operation of said interrupter, a 75 plunger arranged for movement through said arc

chamber, spring means disposed within said spring chamber which normally biases said plunger to the open circuit position, electro-responsive means which normally retains said plunger in the closed circuit position against the biasing force of said spring means, and means for producing an expulsively flowing blast of gas through said arc chamber during each opening operation of said interrupter, said plunger having a portion of conducting material movable through said arc chamber to establish the arc incident to each opening operation of said interrupter therein and a portion of insulating material, also movable through said arc chamber during the operation of said interrupter, to control the physical dimensions of said arc without impeding the free flow of said blast of gas.

22. In an expulsion circuit interrupter, tubular means, at least partially of insulating material, for defining a closure for said interrupter, means 20 within said closure for defining an arc chamber and a spring chamber, the walls of said arc chamber being formed, at least in part, of an insulating material which is capable of evolving an arc extinguishing gas when placed in proximity to an electric arc and at least one end of said arc chamber being open during each opening operation of said interrupter, a plunger arranged for longitudinal movement through said arc chamber, means including a spring disposed 25 in said spring chamber, which normally biases said plunger to the open circuit position, and electro-responsive means for retaining said plunger in the closed position against the biasing force of said spring means, said plunger having a 30 portion of conducting material for establishing the arc incident to each opening operation of said interrupter within said arc chamber and a portion of insulating material which is so proportioned that it effects intimate engagement be- 35 tween said arc and said gas evolving insulating material and permits the flow of gas evolved from said insulating material through said arc pas- 40 sage.

23. In a circuit interrupter, means at least 45 partially of insulating material for defining the walls of an arc passage, means including a fusible element for establishing an arc in said passage, means along the walls of said passage which gives off a gas when acted upon by an arc to aid in 50 extinguishing the arc, said wall defining means having an opening for the escape of gas from said passage, and means of insulating material movable into said passage in response to predetermined conditions for restricting the passage 55 so that the cross sectional area thereof is smaller than that of the restricting means of insulating material movable therein.

24. In a circuit interrupter, means at least 60 partially of insulating material for defining the walls of an arc passage, a movable conducting member of substantially the same cross sectional area as said passage for establishing an arc longitudinally of said passage, a fusible element in circuit with said conducting member, a material 65 along the walls of said passage which gives off a gas when acted upon by an arc to aid in extinguishing the arc and an insulating member movable into said passage in response to the fusion of said element during the circuit interrupting 70 operation for restricting the volume of said passage.

25. In a circuit interrupter, means at least 75 partially of insulating material for defining the walls of an arc passage, means for establishing an arc

in said passage, said arc contacting the walls of said passage to produce an arc extinguishing gas, means for venting said gas from said passage, and means responsive to the magnitude of arc current for controlling the surface area of said passage adapted to be contacted by said arc to effectively extinguish arcs of both large and small current magnitude.

26. In a circuit interrupter, means at least partially of insulating material for defining the walls of an arc passage, means for establishing an arc in said passage, means along the walls of said passage which gives off a gas when acted upon by an arc to aid in extinguishing the arc, said wall defining means having an opening for venting the gas from said passage, and means movable into said passage in response to predetermined current conditions for controlling the quantity of arc extinguishing gas emitted by said gas emitting means to thereby effectively extinguish arcs of both large and small current magnitude.

27. In a circuit interrupter, means at least partially of insulating material for defining the walls of an arc passage, a movable conducting member for establishing an arc longitudinally of said passage, a material along the walls of said passage which gives off a gas when acted upon by an arc, and an insulating member having a cross sectional area less than that of said passage movable in response to predetermined current conditions by said conducting member into said passage, said passage being provided with venting means to cause a blast of gas to flow longitudinally of the arc in a direction opposite to the movement of said insulating member.

28. In a circuit interrupter, means at least partially of insulating material for defining the walls of an arc passage, a plunger arranged for movement through said arc passage, said plunger having a conducting portion normally within said

passage and an insulating portion normally without said passage when the plunger is in the closed circuit position, resilient means biasing said plunger to the open circuit position, a fusible element in circuit with said conducting portion for retaining said plunger in the closed circuit position against the bias of said resilient means, said resilient means being adapted to move said conducting portion through said passage in response to the release thereof by said fusible element to establish an arc within said passage and to move said insulating portion into said passage, said insulating portion having a cross sectional area substantially less than that of said passage.

29. In a circuit interrupter, means defining the walls of an arc passage, means for establishing an arc within said passage, means for venting the products of decomposition of said arc from said passage, means normally positioned without said passage which is movable into said passage to decrease the volume thereof during the operation of said interrupter, actuating means for said movable means and electro-responsive means for preventing said actuating means from moving said movable means into said arc passage except during the existence of certain predetermined conditions.

30. In a circuit interrupter, means defining the walls of an arc passage, means for establishing an arc within said passage, means for venting the products of decomposition of said arc from said passage, means normally positioned without said passage which is movable into said passage to decrease the volume thereof during the operation of said interrupter, means for biasing said movable means into said passage, and electro-responsive means for preventing said biasing means from moving said movable means into said arc passage except on the occurrence of predetermined conditions.
